UNITED STATES PATENT OFFICE.

CHARLES GARGANO, OF ELIZABETH, NEW JERSEY, ASSIGNOR TO FRED GARGANO, OF ELIZABETH, NEW JERSEY.

SAFETY-ENVELOP.

1,211,367.

Specification of Letters Patent. Patented Jan. 2, 1917.

Application filed May 24, 1916. Serial No. 99,664.

To all whom it may concern:

Be it known that I, CHARLES GARGANO, a citizen of the United States, residing at Elizabeth, in the county of Union, State of New Jersey, have invented a new and useful Safety-Envelop; and I do hereby declare the following to be a full, clear, and exact description of the invention, such as will enable others skilled in the art to which it appertains to make and use the same.

The present invention relates to certain new and useful improvements in safety envelops, and has for its object to provide a device of this character which embodies novel features of construction whereby it can not be opened without detection after it has once been sealed.

Further objects of the invention are to provide a safety envelop which can be manufactured at a very slight increase in cost over the ordinary envelop, which can be sealed without difficulty, which has the same exterior appearance as an ordinary envelop, and which will resist all attempts to open the same without mutilation after being once sealed.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a perspective view of a safety envelop constructed in accordance with the invention, all of the flaps being swung upwardly into an open position. Fig. 2 is a transverse sectional view through the safety envelop, the flaps being shown in an open position. Fig. 3 is a similar view, the flaps being closed and the envelop being sealed.

Corresponding and like parts are referred to in the following description and indicated in all the views of the drawing by the same reference characters.

For the purpose of illustration the invention is shown as applied to an envelop of the conventional construction, said envelop including a front 1 upon which the address is adapted to be written, a back 2, and a main sealing flap 3 which is integral with

the upper edge of the front and adapted to be folded rearwardly against the back when the envelop is sealed. A layer 3^a of adhesive may be applied to the inner face of the sealing flap 3, so that it can be readily sealed after being first moistened in the usual manner. The mouth of the envelop is also provided with a pair of auxiliary tissue paper flaps 4 and 5 which are secured to the front and back respectively of the envelop, and are adapted to be folded over the upper edge of the letter and secured by adhesive to the opposite side of the envelop, before closing the envelop with the main sealing flap 3. These interior tissue paper flaps 4 and 5 have a delicate texture and are very easily torn, so that it would be impossible to obtain access to the letter without tearing and mutilating the interior tissue paper flaps, even though the main sealing flap 3 might by some chance be successfully opened. The tissue paper flap 5 is permanently connected at 5^b to the upper edge of the back 2 of the envelop, extending the full length thereof, and fitting against the outer face thereof. The upper end of the tissue paper flap 5 has a layer of adhesive 5^a applied to the outer face thereof, said adhesive being adapted to be employed for securing the flap to the inner face of the front 1 of the envelop when it is folded over the upper edge of the letter. The other tissue paper flap 4 is secured at 4^b to the upper edge of the front 1 of the envelop, extending the full length of the envelop and fitting against the inner face of the front. A layer of adhesive 4^a is applied to the projecting portion of the flap 4, said adhesive being utilized for sticking the flap to the back 2, after the letter is in position within the envelop and the other tissue paper flap 5 has been sealed in the manner previously indicated. The main sealing flap 3 is then closed, said flap 3 being considerably larger than the flap 4, so as to completely cover the same. The tissue paper flaps are thus completely concealed when the envelop is sealed, thereby giving the envelop the same exterior appearance as an ordinary envelop. The layer of adhesive 3^a on the main sealing flap preferably extends over a sufficiently large area to engage a portion of the tissue paper flap 4 when the envelop is sealed, thereby making it practically certain that any effort to lift

the main sealing flap 3 will result in tearing the tissue paper flap. The tissue paper flap 4 may also have lines or characters 6 printed upon the outer face thereof in some form 5 of soluble ink. Any attempt to open the flaps by the use of steam would then cause the ink to smudge and spread in such a manner as to clearly indicate that the envelop had been tampered with, even though by 10 some possibility the adhesive might be softened and the flap raised without tearing.

Having thus described the invention, what I claim as new and desire to secure by Letters Patent, is:—

15 1. As a new article of manufacture, a safety envelop including a body formed with an integral main sealing flap, and a pair of opposed auxiliary tissue paper flaps secured to opposite edges of the mouth of the body portion 20 and extending the full length thereof, said tissue paper flaps being adapted to be folded over each other and secured to opposite sides of the envelop and being concealed by the main sealing flap when the envelop is sealed, 25 said main sealing flap being provided with a layer of adhesive which extends over a sufficiently large area to engage one of the tissue

paper flaps, as well as the back of the envelop.

2. As a new article of manufacture, a 30 safety envelop including a body formed with an integral main sealing flap, and a pair of opposed auxiliary tissue paper flaps secured to opposite edges of the mouth of the envelop and extending the full length of the 35 envelop, said tissue paper flaps being adapted to be folded over each other and secured to opposite sides of the envelop and being concealed by the main sealing flap when the envelop is sealed, one of the tissue paper flaps having characters printed therein with 40 soluble ink which will smear upon the application of steam or moisture, and the main sealing flap being provided with a layer of adhesive which extends over a sufficiently 45 large area to engage the tissue paper flap as well as the back of the envelop.

In testimony whereof I have signed my name to this specification in the presence of two subscribing witnesses.

CHARLES GARGANO.
